UNITED STATES PATENT OFFICE.

HANS C. ELVERS, OF MADISON, WISCONSIN, ASSIGNOR TO GISHOLT MACHINE COMPANY, OF MADISON, WISCONSIN, A CORPORATION OF WISCONSIN.

ADJUSTING AND LOCKING DEVICE FOR CHUCK-JAWS.

1,384,557.

Specification of Letters Patent. Patented July 12, 1921.

Application filed February 12, 1921. Serial No. 444,334.

To all whom it may concern:

Be it known that I, HANS C. ELVERS, a citizen of the United States, residing at Madison, in the county of Dane and State 5 of Wisconsin, have invented certain new and useful Improvements in Adjusting and Locking Devices for Chuck-Jaws, of which the following is a specification.

This invention relates to improvements 10 in chucks for lathes and similar machines employing chucks, and has reference more particularly to an improved device for adjusting and locking the jaw base and jaw on and to the jaw carrier of the chuck. In 15 many chucks the in and out adjustment of the jaw base and jaw on the jaw carrier is effected by a screw, and in such constructions it has been found necessary to provide means for locking the screw against turning movement under the thrust of the chuck jaw.

The principal object of the present invention is to provide an adjusting screw of such a character that it may readily be made self-locking against accidental turning under the 25 thrust of the chuck jaw, to which end the adjusting screw is made in two endwise abutting sections and provided with means by which both sections may be simultaneously and equally turned to effect the adjustment of the jaw, and then one section 30 may be turned relatively to the other to thereby bind the threads of the screw against the threads of the jaw with sufficient friction to avoid danger of accidental turning.

35 My invention, its structural features, and mode or principle of operation will all be readily understood and appreciated by those skilled in the art as the invention becomes better understood by reference to the accompanying drawing, in which I have illustrated one practical and approved embodiment of the invention, and in which—

40 Figure 1 is a longitudinal section through a jaw carrier, jaw base and jaw proper, showing my improved adjusting and locking screw;

Fig. 2 is an end elevation as seen from the right of Fig. 1;

Fig. 3 is a side elevation of a special key 50 for operating the screw; and

Fig. 4 is an end elevation of the tool shown in Fig. 3 as viewed from the left of the latter figure.

Since my present invention relates entirely

to a chuck jaw and its immediate supporting, adjusting and locking means, I have not herein deemed it necessary to illustrate the usual chuck-head; but in the drawing 5 designates the jaw carrier, 6 the jaw base 60 slidably mounted on and relatively to the jaw carrier 5, and 7 the jaw proper secured to the jaw base 6 by the usual counter-sunk cap screws 8. 9 designates a jaw operating lever which is pivoted on the usual back-plate of the chuck, with its short arm engaged with the jaw carrier 5 and its long arm engaged with an endwise movable chuck actuating tube or bar (not shown) that commonly extends axially through the tubular spindle of the chuck, in the manner typically illustrated in Letters Patent to W. L. Miller, No. 1,188,807, June 27, 1916.

In the jaw carrier 5 is mounted for turning movement an adjusting screw comprising two screw sections 10 and 11, the threads 75 of which have the same direction and are of equal pitch. These screw sections are mounted in a tapped lug or boss 12 on the inner face of the screw base 6. The screw section 10 has at its outer end a shank 13 formed with annular shoulders 14 and 15 which are engaged with a coöperating ledge or shoulder 16 on the concave face of the jaw carrier, whereby the screw section 10 is permitted a rotary movement but prevented from moving endwise. 80 The screw section 11 likewise has a shank 17 formed with annular shoulders 18 and 19 which abut against a coöperating ledge or shoulder 20 on the concave face of the jaw carrier, thereby permitting rotary, but preventing endwise movement of the screw section 11.

The screw section 11 and its shank are formed with an axial bore 21, in which is rotatably mounted a round stem 22 on the 95 opposite end of the screw section 10 from its shank 13. The outer end of the shank 17 of the screw section 11 is formed with a rectangular socket 23, and the outer end of the stem 22 of the screw section 10 which extends to or slightly beyond the base of the socket 23 is formed with a transverse kerf 24.

Referring to Figs. 3 and 4, I have thereon shown a special tool designed to manipulate the adjusting screw above described; this 105 tool comprising a stem or shank 25, with a handle 26 passed through the head 27 thereof. The inner end of the shank or stem 25

has a squared portion 28, and on the inner end of this latter is a flat narrow tongue 29. The squared portion 28 fits the socket 23, and the tongue 29 fits the kerf 24.

5 In the use of the device, to adjust the jaw lengthwise of the jaw carrier the adjusting tool is inserted with the squared portion 28 in the socket 23 and the tongue 29 in the kerf 24. By turning the tool in one direction or the other, both screw sections are simultaneously and equally turned, and the jaw base and jaw are adjusted inwardly or outwardly toward or from the center of the chuck-head, until the desired adjustment is 10 reached. The adjusting tool is then withdrawn sufficiently to retract the tongue 29 from the kerf 24, and is then given a further turn in one direction or the other, whereby the screw section 11 is turned a slight distance relatively to the screw section 10. This tends to force the screw sections 10 and 11 either apart or toward each other, and creates sufficient friction in the threads of the screw and at the shoulders 16 15 and 20 to effectively lock the screw against any accidental turning under the thrust of the jaw.

When it is desired to again adjust the jaw, the adjusting tool is entered in the socket 23 30 and turned backwardly until the tongue 29 again registers with and enters the kerf 24, from which point the two screw sections are then turned together until the desired adjustment has been secured, whereupon the screw is again locked in the manner already 35 described.

While I have herein shown and described one practical embodiment of the invention which is characterized by economy and simplicity of structure, it is manifest that the structural details may be considerably varied without departing from the principle involved or sacrificing any of the advantages secured. Hence I reserve all such variations and modifications as fall within the 40 spirit and purview of the appended claims.

I claim:

1. The combination with a jaw carrier, and a jaw base mounted for endwise movement on said carrier, of an adjusting screw rotatably mounted in said carrier and drivingly engaged with said base, said screw being formed in two independently rotatable sections disposed end to end, and means 50 whereby said sections may be simultaneously and equally turned in the same direction and whereby also one of said sections

may be turned independently relatively to the other.

2. The combination with a jaw carrier, 60 and a jaw base mounted for endwise movement on said carrier, of an adjusting screw rotatably mounted in said carrier and drivingly engaged with said base, said screw being formed in two co-axial independently 65 rotatable sections disposed end to end and provided with key-engaging portions disposed one behind the other, and a key adapted to simultaneously engage with both of said key-engaging portions whereby to turn 70 both of said screw sections, and also adapted, when partially withdrawn, to engage with and turn said outer key-engaging portion only.

3. The combination with a jaw carrier, 75 and a jaw base mounted for endwise movement on said carrier, of an adjusting screw rotatably mounted in said carrier and drivingly engaged with said base, said screw being formed with two sections disposed end 80 to end, one of said sections having an axial bore terminating at its outer end in a key-engaging member, and the other section having a stem mounted in said bore and terminating at its outer end in a key-engaging member located inwardly of said first-named key-engaging member, and a key provided with portions adapted to drivingly engage with both said key-engaging members to effect simultaneous equal 90 rotation of said screw sections, and, when partially withdrawn, to engage only with said first-named key-engaging member whereby to effect a relative turning movement of said screw sections to thereby lock 95 said screw against accidental turning.

4. The combination with a jaw carrier, and a jaw base mounted for endwise movement on said carrier, of an adjusting screw rotatably mounted in said carrier and drivingly engaged with said base, said screw being formed in two co-axial sections disposed end to end, one of said sections having an axial bore terminating at its outer end in a key-engaging socket, and the other section 100 provided with a stem mounted in said bore and terminating at its outer end in a key-engaging socket located inwardly of said first-named socket, and a key provided with endwise alined socket-engaging portions 110 shaped to fit the respective sockets of said screw sections.

HANS C. ELVERS.
